UNITED STATES PATENT OFFICE.

THOMAS DAWSON, OF BEVERLY, MASSACHUSETTS, ASSIGNOR OF ONE-HALF TO
SAMUEL F. THOMPSON, OF SPRINGFIELD, MASSACHUSETTS.

SEASONING-MACHINE.

1,074,588.

Specification of Letters Patent. Patented Sept. 30, 1913.

Application filed August 14, 1912. Serial No. 715,083.

To all whom it may concern:

Be it known that I, THOMAS DAWSON, a citizen of the United States of America, and resident of Beverly, in the county of Essex 5 and State of Massachusetts, have invented certain new and useful Improvements in Seasoning-Machines, of which the following is a full, clear, and exact description.

This invention relates to machines for 10 treating hides or skins in the process of applying seasoning or filling liquor to the surface of the skin whereby it is rubbed in and at the same time the skin is manipulated and stretched to be thoroughly subjected to the liquor.

One of the objects of the invention is to provide an arrangement of rolls whereby the hide will be caused to be fed between a pair of coöperating rolls, and a third roll 20 can be brought to engage one face of the hide by pressure regulated as desired.

A further object is to provide means for feeding the seasoning liquid from a suitable trough or receptacle onto such rolls 25 and to cause the liquor to be fed by the operation of bringing the said third roll into engagement with the hide.

A further object is to provide means operated by the said movement of the third 30 roll whereby the liquor in a suitable receptacle will be properly agitated.

Another object is to provide one of the feeding rolls with a surface of soft rubber and to also provide the third roll which is 35 brought to engage the hide by variable pressure with a number of strips of fabric arranged in the form of a scroll to cause the hide to be properly stretched.

A further object is to provide in connection with such third rolls, one of which is in the nature of a comparatively large drum, an additional pair of rolls for the subsequent treatment of the hide, with means for bringing said rolls into the proper degree of contact or pressure on the hide; and one of 45 which latter rolls can be shifted to be brought into engagement with the drum in advance of its position of engagement with the other two rolls whereby the drum and 50 such roll can be utilized for the second treatment of the hide.

In the accompanying drawings showing one embodiment of my invention,—Figure 1 is an end elevation; Fig. 2 is an elevation 55 of the opposite end; Fig. 3 shows enlarged

a vertical section; Fig. 4 is a detail view showing the scroll roll and the drum with the means for giving them rotation and also endwise movement to the scroll roll; Fig. 5 is a side elevation of the machine. 60

In the drawings, the machine is shown as provided with a suitable frame denoted generally by 6, provided with a shelf or table 7 on which the hide is laid for feeding.

The drum 8 is mounted on a shaft 9 suitably supported in bearings at its extremities, this shaft having a gear 10 meshing with a pinion 11 on a shaft 12 extending across the machine. This latter shaft also carries a pulley 13 driven by belt 14 from 65 a suitable source of power, such as an overhead shaft 15 and pulley 16 thereon.

The shelf 7 extends across the upper part of the roll 8 in position to feed the hide onto the top of the roll. A short distance 75 beyond, at the upper part of the roll or drum 8 is arranged a feed roll 17 carried by a shaft 18 rotatable in suitable bearings in the frame. A sprocket 19 on the shaft 18 is connected with a sprocket 20 on the shaft 80 12 by a sprocket chain 21, as best shown in Fig. 2; and by this means the drum 8 and roll 17 are rotated in opposite directions, which will cause their adjacent portions to move in the same direction to advance the 85 hide when presented between their surfaces.

The bearings 22 for the shaft 18 are slideable in a slot 23 in the frame on each side and moved upward by a spring 24 against the adjusting bolt 25, by which means the 90 positioning of the roll 17 relative to the drum can be nicely regulated. The roll 17 is preferably coated with soft rubber on its periphery; and this roll has the seasoning liquor fed onto it and carries it around to 95 engage the hide as it passes between this roll and the drum.

The trough 26 is shown as of cylindrical form and supported by journals 28, 28 at the extremities thereof to be rocked on its 100 axis. Along one side of the trough 26 are a series of openings 29 in horizontal alignment, and upon the trough being filled up to these openings, a slight swing of the trough to lower the openings will cause the liquor therein to be precipitated upon the roll 17 above which the trough is mounted. For feeding the trough 26, a receptacle 30 is arranged on an extension 31 of the frame, and a plug 32 therein serves to permit the liq- 110

uor to flow out from the receptacle and fall into an opening 33 in the top of the trough 26; the plug 32 serves to regulate the flow of the liquor as it may be needed.

5 Directly above the drum 8 is arranged a scroll roll 34 having its shaft 35 carrying a gear 36 which meshes with a gear 37 fast on the shaft 18 of the feed roll 17 by which means the scroll roll is rotated. The shaft 10 35 of the scroll roll is mounted in bearings in a pair of levers 38 and 39 pivoted on the bearing blocks 22 of the feed roll 17, and by swinging these levers the scroll roll can be moved to and from the drum 9, yet retain its 15 relative position to the roll 17, preferably in contact therewith.

At the base of the machine is a treadle 40 connected by rods 41 and 42 with the levers 38 and 39 respectively, and a spring 43 20 serves to normally retain the treadle elevated and also the levers to hold the scroll roll above and free from the drum 8.

After the hide has been placed on the table and passed over the drum 8 to be engaged between the roll 17 and the drum, the treadle is depressed, which will bring the scroll roll down onto the hide by pressure varying according to the force exerted on the treadle. The scroll roll 34 is shown as provided on its face with spaced strips of felt or other fabric 44 extending in opposite spiral directions from the middle portion for the purpose of spreading out the hide and distributing the liquor over its surface. It 30 will be noticed that the scroll roll 34 is driven directly from the shaft of the feed roll 17 by gears, and hence it will be rotated in the same direction as the drum, but the adjacent surfaces will move in the opposite directions, which will facilitate the spreading out of the hide and the distribution of the liquor over its surface.

The swinging trough 26 is provided at its ends with arms 45 which are connected by 45 links 46 with the levers 38 and 39, so that when the treadle is depressed to swing the levers and cause the scroll roll to engage the hide, the trough will be rocked and spill some of its liquor through the line of openings onto the rubber feed roll 17; and when the levers return the trough will be swung back and no liquor will be fed until another hide is presented to the rolls. Means are further provided for agitating the liquor in 50 the trough 30; a weight or bar 47 is connected at its ends with cables 48, 49, passing over guide pulleys 5, 1, in the ceiling or roof, and secured to the levers 38 and 39 respectively; by which means the swinging 55 of the levers will cause the weight to move up and down in the receptacle and keep the seasoning liquor properly mixed.

After the hide has been subjected to the treatment by the three rolls, it may be given 60 additional treatment by means of another

roll 50 having its shaft 51 mounted in bearing blocks 52 adjustable on the frame by means of a hand wheel 53 and screw 54, the latter engaging a nut 55 on the bearing blocks. This roll 50 may be thereby shifted over into proximity to the drum 8, and the hide can be treated between these two members, the operator receiving the hide after it passes beyond the rolls 17 and drum 8 and presenting it between the drum and roll 50. Or, if desired, the hide may be passed 70 between the roll 50 and a plain cylindrical brush roll 56 mounted on a pair of arms 57 and 58 suitably pivoted on the frame, which are connected with a treadle 59 by links 60', 61'; by which means the brush roll 56 can be caused to press the hide against the roll 50 with the desired amount of pressure.

The scroll roll 34 during its rotation is also given an endwise movement, this shaft 35 being slidable in the levers 38 and 39, and a coil spring 60 between one end of the roll and the lever 39 serving to press a cam ring 61 on the other end of the roll against a roller 62, on the lever 38; the gear 36 being provided with a wide face so that the gear 37 will not be shifted out of engagement therewith during its endwise movement of the roll. This will further facilitate the distribution of the liquor over the 95 surface of the hide and serve to properly stretch the same and to work the liquor into its surface.

A suitable trough 65 may be provided below the drum 8 and also below the roll 50 100 to receive the surplus liquor which may drain off from the rolls or from the hides being treated.

I claim:

1. In a seasoning machine, a frame, a drum rotatably mounted in the frame, a feed roll rotatably mounted in the frame, means for rotating both the said members, a scroll roll rotatably mounted in the frame and movable to and from the drum, means for rotating the scroll roll during its said movement, a liquor trough mounted above the feed roll, and means for moving the scroll roll to and from the drum and at the same time causing the trough to feed liquor onto the feed roll. 115

2. In a seasoning machine, a frame, a drum rotatably mounted in the frame, a feed roll rotatably mounted in the frame, means for rotating both the said members, a scroll roll rotatably mounted in the frame and movable to and from the drum, means for rotating the scroll roll during its said movement, a liquor trough mounted above the feed roll, means for moving the scroll roll to and from the drum and at the same time causing the trough to feed liquor onto the feed roll, and an agitator for the liquor connected with said roll moving means to be operated thereby. 120 125 130

3. In a seasoning machine, a frame, a drum rotatably mounted in the frame, a feed roll rotatably mounted in the frame, means for rotating both the said members, a scroll roll rotatably mounted in the frame and movable to and from the drum, means for rotating the scroll roll during its said movement, a liquor trough mounted above the feed roll, and means for moving the scroll roll to and from the drum and at the same time causing the trough to feed liquor onto the feed roll, a set of bearings adjustable on the frame, and a felt roll mounted in said bearings to be shifted into and out of engagement with said drum beyond said feed roll to engage the hide after being operated upon by said roll.
4. In a seasoning machine, a frame, a drum rotatably mounted in the frame, a feed roll rotatably mounted in the frame, means for rotating both said members, a pair of levers pivoted at the ends of the feed roll to swing on the same axis as the feed roll, a scroll roll mounted to rotate on bearings in said levers in engagement with the feed rolls during the swinging of the levers and to be thereby shifted to and from the drum, and means for simultaneously swinging the levers.
5. In a seasoning machine, a frame, a drum rotatably mounted in the frame, a feed roll rotatably mounted in the frame, means for rotating both said members, a pair of levers pivoted at the ends of the feed roll to swing on the same axis as the feed roll, a scroll roll mounted to rotate on bearings in said levers in engagement with the feed rolls during the swinging of the levers and to be thereby shifted to and from the drum, and means for simultaneously swinging the levers, a liquor trough mounted above the feed roll, and means for causing the trough to feed liquor onto the feed roll from the swinging of said levers to move the feed roll to engage the drum.
6. In a seasoning machine, a frame, a drum rotatably mounted in the frame, a feed roll rotatably mounted in the frame, means for rotating both said members, a pair of levers pivoted at the ends of the feed roll to swing on the same axis as the feed roll, a scroll roll mounted to rotate on bearings in said levers in engagement with the feed rolls during the swinging of the levers and to be thereby shifted to and from the drum, means for simultaneously swinging the levers, a liquor trough mounted above the feed roll, to swing on an axis to feed liquor onto the feed roll, and connections between the trough and the levers to cause the swinging of said levers to move the feed roll to engage the drum.
7. In a seasoning machine, a frame, a drum rotatably mounted in the frame, a feed roll rotatably mounted in the frame, means for rotating both of said members, a pair of levers pivoted at the ends of the feed roll to swing on the same axis as the feed roll, a scroll roll mounted to rotate on bearings in said levers in engagement with the feed rolls during the swinging of the levers to be thereby shifted to and from the drum, means for simultaneously swinging the levers, a liquor trough mounted above the feed roll, means for causing the trough to feed liquor onto the feed roll from the swinging of said levers, a cable connected with said levers, a weight connected with said cable, and guides supporting the cable with the weight suspended in the trough, whereby the swinging of the levers will cause the cable to lower and raise the weight, and a feed tank above the trough in which the weight is moved to agitate the liquor therein.
8. In a seasoning machine, a frame, a drum rotatably mounted in the frame, a feed roll rotatably mounted in the frame, means for rotating both said members, a pair of levers pivoted at the ends of the feed roll to swing on the same axis as the feed roll, a scroll roll mounted to rotate on bearings in said levers in engagement with the feed rolls during the swinging of the levers and to be thereby shifted to and from the drum, means for simultaneously swinging the levers, means for rotating the scroll roll during the swinging of the levers, means for shifting the scroll roll endwise during its rotation, a liquor trough mounted above the feed roll, and means for causing the trough to feed liquor onto the feed roll.
